UNITED STATES PATENT OFFICE.

GEORGE J. STENGEL, OF YONKERS, NEW YORK, ASSIGNOR TO W. & J. SLOANE, OF NEW YORK, N. Y., A CORPORATION OF NEW YORK.

DESIGN FOR A CARPET, RUG, OR SIMILAR ARTICLE.

51,217.

Specification for Design.

Patented Aug. 28, 1917.

Application filed July 2, 1917. Serial No. 178,262. Term of patent 3½ years.

To all whom it may concern:

Be it known that I, GEORGE J. STENGEL, a citizen of the United States, residing at Yonkers, in the county of Westchester and State of New York, have invented a new, original, and ornamental Design for a Carpet, Rug, or Similar Article, of which the following is a specification, reference being had to the accompanying drawing, forming part thereof.

The figure of the drawing is a view of so much of a carpet as is necessary to show my new design.

I claim:

The ornamental design for a carpet, rug or similar article, as shown.

GEORGE J. STENGEL.
